Primary Examiner — Selina Sikder(74) *Attorney, Agent, or Firm* — Fitch, Even, Tabin & Flannery LLP(57) **CLAIM**

We claim the ornamental design for movable barrier operator device, as shown and described.

DESCRIPTION

FIG. 1 is a bottom perspective view of the movable barrier operator device showing our new design;

FIG. 2 is a top perspective view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a front elevation view thereof; and,

FIG. 8 is a rear elevation view thereof.

The dash-dash broken lines in the drawings depict portions of the movable barrier operator device that form no part of the claimed design. The dash-dot-dash broken lines immediately adjacent to the shaded surfaces depict (represent or indicate) a boundary of the claimed design, and form no part of the claimed design.
